RALEIGH CLARK AND ONE-THIRD TO BLAINE HUFFMAN, BOTH OF LAWRENCE-
VILLE, ILLINOIS.

AUTOMATIC GAS CUT-OFF.

1,290,660.

Specification of Letters Patent.

Patented Jan. 7, 1919.

Application filed August 22, 1918. Serial No. 250,987.

To all whom it may concern:

Be it known that I, CLARENCE N. RETTIG, a citizen of the United States, and resident of Lawrenceville, in the county of Lawrence and State of Illinois, have invented certain new and useful Improvements in Automatic Gas Cut-Offs, of which the following is a specification.

This invention relates to an improvement 10 in automatic gas cut-offs, designed to prevent gas from escaping into a room or rooms when due to the falling of the gas pressure or failing of the gas supply in the main leading to the burners, the latter when lighted 15 will be extinguished, the improvements contemplated in the provision of means to prevent the escape of gas when the pressure in the main is resumed.

A further object of the invention is to provide 20 an improved automatic gas cut-off of the character mentioned, which can be associated with the gas supply pipe and is interposed between the supply pipe and the burners, so as to permit the supply of gas to the latter when there is a proper supply of gas 25 under normal pressure, but which will automatically cut off the gas supply upon the pressure being resumed after having been temporarily cut off or having failed, thereby preventing accidents or asphyxiation, as 30 would occur were the gas allowed to escape freely into the room or rooms.

With the above and other objects in view, as will appear as the description proceeds, 35 the invention comprises the various novel features of construction and arrangement of parts which will be more fully described herein and set forth with particularity in the claims appended hereto.

40 Reference is had to the accompanying drawings forming a part of this application, in which like reference characters indicate the corresponding parts throughout the several views, in which—

45 Figure 1 is a side elevation of my improved automatic gas cut-off.

Fig. 2 is a vertical longitudinal sectional view thereof centrally or axially of the device, and

50 Fig. 3 is a cross sectional view, taken on the line 3—3 of Fig. 2.

Referring to the drawings in detail, my improved automatic gas cut-off comprises a cylinder formed of sections 10 and 11, the

same being of cylindrical outline, in the preferred embodiment, and having flanges 12, through the medium of which the sections are bolted together at their open inner ends. The outer end of the section 10 is closed with the exception of a small aperture through 55 a reduced extension 13 thereof, while the opposite end of the section 11 has connection with a gas supply pipe 14 leading from the main.

When the sections 10 and 11 are connected 60 through the medium of the flanges 12, a flexible diaphragm 15, preferably of leather, is held between said sections or flanges thereof and has extending therethrough, a plunger 16 located axially of the casing produced by said sections. This plunger in the 65 form of an axial stem or rod, has the diaphragm anchored thereto through the medium of a plate or flange 17 on one side and a nut 18 on the other side threaded on the 70 plunger, so as to prevent the escape of gas 75 from the section 11 into the section 10 to any appreciable extent.

The plunger 16 has mounted thereon a pair of spaced circular plates 19 in fixed 80 parallel relation and adapted to be spaced from the wall of the section 11 to one side of its connection with the section 10, the opposite end of said plunger extending through the extension 13 through the medium of an 85 aperture 20 therein, which serves as a guide for the plunger. The end of the plunger projects from the extension 13 and a cap 21 is threaded externally on the extension so as to form a gastight joint and protect the end 90 of the plunger.

Positioned between the plates 19 is a ball 22, and depending from the section 11 adjacent to the end wall thereof to which the gas pipe 14 is connected, is an extension or 95 valve casing 23 provided with a ground seat 24 into which the ball is designed to drop, as will be hereinafter specified. The extension 23 has an apertured division wall 25 and above the same an internally threaded extension 26 for connection with a gas pipe 27 leading to the burners or various apparatus for consumption. The extension below the apertured division wall 25 has a cap 28 externally threaded thereon, the lower portion 100 of the extension being designed to accommodate a finger, while the division wall has slidably mounted therein for vertical move-

ment a spindle 29 which projects to a point below the valve seat 24.

There is also provided upon the plunger 16, an expansible coil spring 30, which normally tends to hold the diaphragm 15 toward the section 11, but in the operation of the device, when the pressure is on the main and gas is discharged from the pressure under supply pipe into the casing, the diaphragm 15 is moved to the right hand position indicated in Fig. 2, thereby compressing the spring 30 and holding the ball 22 between the plates 19 on the bottom portion of the casing section 11 beyond the valve seat 24 communicating with the bottom of the casing. In the event that the pressure should fail or decrease to such an extent as to extinguish the burners, the spring 30 will immediately act to shift the plates 19 to the left or on either side of the valve seat 24, thereby permitting the ball-valve 22 to drop into said seat to prevent escape of gas into the pipe 27 from the supply pipe 14 and casing when the pressure has resumed. This will prevent the escape of gas from the burners or other apparatus consuming the same, and prevent the gas from escaping into a room or rooms and causing asphyxiation or other accidents.

30 However, in order to reset the apparatus, the cap 21 is removed and the plunger 16 forced to a position over the valve seat 24 against the action of the gas pressure so that the plates 19 will straddle the valve seat and 35 with the cap 28 removed the stem 29 is elevated to raise the ball 22 between the plates 19 and while held in this position, the plunger 16 is released or pulled outwardly assisted by the gas pressure against the 40 action of the spring 30. The cap 28 is then replaced, the stem 29 dropping and being limited in its downward displacement, but permitting the passage to the pipe 27 to be cleared and open whereby the gas will pass 45 to the burners or other apparatus consuming the same, in the usual manner. It will also be observed that the upper end of the stem is provided with a flange 31 for unseating the valve, and it will be obvious that 50 when the valve is seated or closed, the gas cannot escape into the section 10 beyond the diaphragm and the greater the pressure, the harder the valve will be seated to positively cut off the supply of gas to the burners.

55 From the foregoing description taken in connection with the accompanying drawings, it is thought that a clear and comprehensive understanding of the construction, operation, and advantages of my invention may 60 be had, and while I have shown and described the device as embodying a specific structure, I desire that it be understood that such changes may be made in said structure as do not depart from the spirit and scope 65 of the invention as claimed.

Having thus described my invention, what I claim as new and desire to secure by Letters Patent, is:

1. In an automatic cut-off, a horizontal casing, a supply pipe for fluid pressure connected to one end of the casing, a diaphragm in the casing and dividing the same longitudinally, a plunger movable through the end of the casing remote from the pipe connection and projecting toward the latter beyond the diaphragm, said diaphragm being fixedly connected to the plunger, a pair of spaced members carried by the plunger at the inner end thereof and permitting the passage of fluid past the same to the plunger, means normally holding the plunger inwardly displaced and adapted to permit opposite displacement thereof with the diaphragm and spaced members under the pressure of the fluid, said casing having a depending extension provided with a valve seat and a ball designed to be held between said spaced members and adapted to drop into said depending extension upon the pressure decreasing and permitting the diaphragm to be forced inwardly, said depending extension having an outlet leading therefrom, placed in communication with the supply through the casing when the ball is unseated and cut-off when the ball is seated. 95

2. An automatic gas cut-off comprising a sectional casing, a diaphragm therein, a spring plunger associated with the diaphragm to hold the latter distended, said casing having connection with the gas supply main, a pair of spaced plates on the plunger, a ball positioned between said plates and held to one side by the action of the gas pressure against the diaphragm, an outlet extension having a valve seat, into which said valve is adapted to fall when the pressure decreases, due to shifting of the plates through the medium of said spring plunger, and an outlet pipe leading from the extension to the burners. 110

3. An automatic gas cut-off comprising a sectional casing, a diaphragm therein, a spring plunger associated with the diaphragm to hold the latter distended, said casing having connection with the gas supply main axially at one end, a pair of spaced plates on the plunger and spaced from the inner wall thereof, a ball positioned between said plates and held to one side by the action of the gas pressure against the diaphragm, an outlet extension having a valve seat into which said ball is adapted to fall when the pressure decreases, due to shifting of the plates through the medium of said spring plunger, said extension having a supply pipe leading therefrom, means for shifting said plunger against the action of the spring, and means for unseating the valve to position the same between said plates. 125

4. An automatic gas cut-off comprising a 130

- sectional casing, a diaphragm therein, a spring plunger associated with the diaphragm to hold the latter distended, said casing having connection with the gas supply main at one end, a pair of spaced plates on the plunger between the diaphragm and connection of the casing with the main, a ball positioned between said plates and held to one side by the action of the gas pressure against the diaphragm, an outlet extension having a valve seat into which said ball is adapted to fall when the pressure decreases, due to shifting of the plates through the medium of said spring plunger, a supply pipe leading from said extension, means for shifting said plunger against the action of the spring, said diaphragm being connected between said sections of the casing, said ball being held from being unseated when the pressure decreases or ceases, and a stem mounted in the extension depending from the casing below the valve seat for unseating said ball to position the same between said plates, whereby said ball may be moved to a position to one side of the valve seat.
5. An automatic gas cut-off comprising a sectional casing, a diaphragm therein, a spring plunger associated with the diaphragm to hold the latter distended, said casing having connection with the gas supply main, a pair of spaced plates on the plunger, a ball positioned between said plates and held to one side by the action of the gas pressure against the diaphragm, an outlet extension having a valve seat into which said ball is adapted to fall when the pressure decreases, due to shifting of the plates through the medium of said spring plunger, said extension having a supply pipe leading therefrom, means for shifting said plunger against the action of the spring, said diaphragm being connected between said sections of the casing, when said sections are secured together, said ball being held from being unseated when the pressure decreases or ceases, a cap for said spring plunger, said plates being smaller than the interior of the casing and adapted to be drawn to one side by movement of the plunger against the action of said spring, a vertical stem operating in the outlet extension and having a flange in its upper end engaging the ball to unseat the same by upward movement of the stem, and a cap for the lower end of the extension, as and for the purposes specified.
- 10 15 20 25 30
- In testimony whereof, I affix my signature hereto.

CLARENCE N. RETTIG.
